CONTAINER WITH SANITARY END CLOSURE

Howard M. Hill, Port Washington, N. Y., assignor to American Can Company, New York, N. Y., a corporation of New Jersey

Application December 30, 1953, Serial No. 401,116

1 Claim. (Cl. 229—7)

The present invention relates to containers for the packaging and delivery of liquids, such as milk and the like and has particular reference to a sanitary fibre container of an improved construction which embodies a multiple layer, reinforced dispensing top closure having a hingeable protective shield.

The invention constitutes an improvement upon the container disclosed in United States Patent 2,609,985 issued September 9, 1952 to George C. Reid, et al.

An object of the instant invention is the provision of a dispensing top closure for a container wherein the area around the dispensing opening is reinforced with an additional layer of material and is also protected against unsanitary conditions, so that a strong, rigid top closure may be provided by using a sheet material of reduced thickness.

Another object is the provision of such a dispensing top closure which may be made from a single piece of material and folded in such a manner as to provide for the reinforcing layer of material on one side and a protective hingeable shield overlying the dispensing opening on the opposite side, so as to facilitate manufacture and handling of the closure as a unit preparatory to assembling it to a container.

Numerous other objects and advantages of the invention will be apparent as it is better understood from the following description, which, taken in connection with the accompanying drawings, discloses a preferred embodiment thereof.

Referring to the drawings:

Figure 1 is a perspective view of the upper end of a sealed container embodying the instant invention;

Fig. 2 is an enlarged sectional view taken substantially along a plane indicated by the broken line 2—2 in Fig. 1, with parts broken away;

Fig. 3 is a reduced scale sectional view taken through the top closure alone;

Fig. 4 is a top plan view of a blank from which the top closure of the container shown in Fig. 1 is constructed;

Fig. 5 is a plan view of the reverse side of the blank shown in Fig. 4;

Fig. 6 is a perspective view showing how the blank shown in Figs. 4 and 5 is folded to produce the closure; and

Fig. 7 is a top plan view of the folded closure.

As a preferred or exemplary embodiment of the instant invention the drawings illustrate a rectangular container comprising a fibre tubular body 11 (Fig. 1) closed at its upper end with a sanitary, flat, fibre dispensing top closure 12. The bottom end of the container may be closed in any suitable manner.

The body 11 preferably is formed from a single sheet or blank of fibrous material folded at right angles to provide four side walls and having the side edges of the blank overlapped and adhesively secured together to form a lap side seam 14 (Fig. 1).

The body side walls adjacent their upper ends are

2

formed with an inwardly extending oblique wall section 16 (Figs. 1 and 2) which merges into a short vertical wall section 17 defining a mouth for the container. The terminal end of the short wall section 17 merges into an outwardly extending peripheral, flat horizontal shoulder 18, the outer peripheral edge portion of which curves upwardly and thence inwardly as a bent back flange 19 disposed in spaced and parallel relation to the shoulder 18. The shoulder 18 and flange 19 thus provide a U-shaped receiving channel 20 for reception of the marginal edge portions of the top closure 12.

The top closure 12 preferably is made from a one-piece blank 22 (Figs. 4 and 5) of fibrous sheet material. The blank 22 is irregular in shape and includes a substantially rectangular outer portion 23 and an adjacent similar intermediate portion 24 joined by a fold line 25. Extending from the intermediate portion 24, the blank includes a triangular or fragmental inner portion 27 of substantially one half the area of the intermediate portion 24 and joined to this portion by a fold line 28 spaced from and disposed parallel to the fold line 25.

In such a blank 22, the intermediate portion 24 is defined by the two parallel fold lines 25, 28 and two outer straight parallel edges 31, 32. The triangular inner portion 27 is defined by the fold line 28, an outer straight edge 33 which is coextensive with the outer edge 31 of the intermediate portion 24, and a diagonal or base edge 34 which extends from the terminal end of the triangular edge 33 to the opposite corner of the intermediate portion 24 as defined by the intersection of the fold line 28 and the outer edge 32 of the portion 24.

Along two sides, the outer portion 23 is defined by the fold line 25, and an outer edge 35 which is coextensive with the outer edge 32 of the intermediate portion 24. The remaining two adjoining sides of the outer portion 23 are irregular in contour and project outwardly to provide overhanging connected peripheral flanges 36, 37. Flange 36 extends beyond the outer edge 31 of the intermediate portion 24 and is defined by a curved corner edge 39 partially cut from the corner of the intermediate portion 24, a connecting sloping edge 40 and an edge 41 which is parallel with the edge 31.

At the corner of the outer portion 23 where the flange 36 merges with the flange 37, a curved edge 43 defines the corner of the blank. The flange 37 is defined by a straight edge 44 which is a continuation of the curved edge 43, a connecting sloping edge 45 and a continuing curved corner edge 46 which terminates at the side edge 35 of the blank 22. The curved corner edges 39, 46 set off corner lobes 47, 48 respectively at the terminal ends of the flanges 36, 37. The terminal ends of these curved edges 39, 46 also are connected by a fold line 51 which extends diagonally from corner to corner across the outer blank portion 23 and sets off a hingeable triangular shaped shield portion 52 which includes the flanges 36, 37. A pair of short slits 54, 55 are also provided in the outer portion 23. These slits extend inwardly from the outer edge 35 and the fold line 25 and are parallel with and in spaced relation to the hinge fold line 51. A short slit 56 at the fold line 25 extending from the slit 55 to the curved corner edge 39, is also provided for assembly purposes as will be hereinafter explained.

To produce the dispensing top closure 12 the blank 22 is folded along the parallel transverse fold lines 25, 28 as shown in Fig. 6 to form a three layer, ply or thickness rectangular closure. In this closure the outer portion 23 is on top and comprises the outer layer, the intermediate portion 24 is under the outer layer and comprises the intermediate layer, and the triangular inner

portion 27 is on the bottom in vertical alignment with the triangular shield 52 of the outer layer and comprises the inner, or reenforcing layer. The flanges 36, 37 of the outer or top layer 23 extend beyond the outer edges of the folded-under intermediate and inner layers 24 and 27 as shown in Fig. 7. A suitable adhesive 58 applied to portions of the blank 22 in predetermined locations, as for example the designs shown in Figs. 4 and 5 is utilized to secure the layers together to provide a solid unitary closure. This adhesive is omitted from the triangular shield 52 and the portion of the outer layer 23 immediately under the shield so that the shield is free.

After thus folding the blank 22 and adhesively securing the three layers 23, 24, 27 together, a circular opening 61 is punched through all three layers of the closure in a location adjacent the corner covered on the top by the triangular shield 52 and on the bottom by the triangular inner layer 27 as shown in Fig. 7. This opening 61 in the intermediate layer 24 and the inner layer 27 serves as a filling and dispensing opening for the closure, the material around the opening being reinforced by the inner layer 27. In the outer layer 23, the opening 61 serves as a clearance opening or seat for a friction plug 62 (Figs. 2 and 3) to seal the dispensing opening. The plug 62 is formed with a surrounding flange 63 and a tab 64 which are adhesively secured to the outer face of the shield 52 and are liftable together.

In the container, the outer marginal edge portion of the closure 12, excepting the shield portion 52, as defined by the fold lines 25, 28, outer coincident edges 31, 33 and outer coincident edges 32, 35 fit into the peripheral channel 20 of the container body and are adhesively secured to the shoulder 18 and bent back flange 19 of the body as shown in Figs. 1 and 2 to produce an end seam 66 which projects laterally from the container body 11 and which permanently secures the dispensing top closure 12 to the body.

The shield portion 52 of the outer layer 23 of the closure 12 overlies the opposed portions of the end seam 66, from the slit 54 to the slit 55, including three corners of the seam as shown in Fig. 1 so as to permit the shield to be hinged up into a vertical position to expose the opening 61 for the filling of the container.

The peripheral flanges 36, 37 of the shield 52 and the tab 64 of the friction plug 62 adhesively secured to the shield, extend beyond the top of the container and are folded over and beneath the end seam 66. After the container is filled these flange portions are clinched in place to hold the shield against accidental opening. The corner lobes 47, 48 are also crimped under the corners of the seam. The friction plug 62 is also expanded as shown in Fig. 2 to seal the opening 61.

Thus while the triangular inner layer 27 of the closure 12 reenforces the closure around the filling and dispensing opening 61, the top or outer layer 23 provides a fixed portion which is secured in the end seam 66 and an integral hinged shield portion 52 which protects the pouring surfaces of the top and end seam 66 adjacent the opening 61 and which shield portion carries the ad-

hesive secured friction plug 62 which seals the opening 61.

To open the container, the corner of the shield 52 and the tab 64 of the friction plug are pulled from under the end seam 66 and used as a finger hold for lifting the shield and pulling the plug out of the opening 61. This exposes the opening so that it may be used for filling or dispensing the contents of the container.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

A container for liquids, comprising a tubular fibre body of substantially square cross section and a flat top closure of integral triple thickness secured thereto in a laterally projecting end seam, said top closure having a filling and dispensing opening therein and being composed of relatively thin material including an intermediate layer of substantially square configuration, an integral inner layer of triangular configuration extending from one end of the intermediate layer and folded against and adhesively secured to the under surface of said intermediate layer to form one diagonal half of a substantially square composite reenforcing layer for the top closure, said opening being in said intermediate and triangular layers, an outer layer including a triangular portion formed integrally with and extending from the other end of the intermediate layer and folded against and adhesively secured to the upper surface of the intermediate layer to form the other diagonal half of said composite reenforcing layer, said diagonal halves together being coextensive with and adhesively secured to opposite surfaces of said substantially square intermediate layer for reenforcing said opening, and a substantially triangular hingeable shield forming integrally with and extending from said triangular outer layer reenforcing portion and set off therefrom by a diagonal line of fold along a hypotenuse common to said triangular inner reenforcing layer and to said triangular reenforcing portion of the outer layer, and a friction plug carried by said shield for closing and sealing said opening.
